UNITED STATES PATENT OFFICE

JAMES D. SHEPHERD, OF CHICAGO, ILLINOIS

SHOE

Application filed July 31, 1929. Serial No. 382,331.

This invention relates to safety shoes.

One of the objects of the invention is in the provision of a safety shoe ordinarily used for industrial purposes, the same being provided with a box toe member formed of bakelite or, rather, a phenolic condensation product.

Another object of the invention is in the provision of a safety shoe so formed as to permit the use of a phenolic condensation product box portion, the same having such properties and such resistance to impact as to provide the most satisfactory safety shoe construction known at this time.

Still another object lies in the provision of a safety shoe wherein a phenolic condensation product box stiffener is used to provide protection for the toes of shoes of industrial workers.

A further object is in the method of forming a safety shoe, said method permitting the use of a phenolic condensation box member in connection with the insole, lining, leather, welt and outsole portions.

A still further object lies in the provision of a safety shoe which utilizes a box member having such properties as will not only practically obviate accidents to the toes of the wearer, but also insure a shoe constructed with such an efficient method as will increase greatly not only the life of the shoe but also enhance the appearance thereof.

Other objects will appear in the following specification taken in connection with the annexed drawings, in which—

Fig. 1 is a plan view from above of the toe portion of my safety shoe, there being a diagrammatic showing of the position of the phenolic condensation box stiffening member therein;

Fig. 2 is a cross-sectional view, taken on the line 2—2 of Fig. 1;

Fig. 3 is an enlarged detail, showing the method of attaching the various portions of the shoe;

Fig. 4 is a longitudinal sectional view showing the manner of placement of the phenolic condensation box within the toe portion of the shoe; and

Fig. 5 is a perspective of the bakelite or

phenolic condensation box stiffening member.

Before referring specifically to the drawings, it might be well to trace somewhat the history and development of safety shoes. These are used primarily for industrial purposes and came into prominence following the world war, until at the present time they are used by practically every large industrial organization, being sold in almost every instance by the manufacturer to the industrial organization for direct re-sale to its employees. Obviously, the use of such safety shoes by large industrial organizations is for the purpose of obviating accidents, the majority of which occur to the toes of various machine operators or employees of any character. It may be stated as a matter of fact that the use of this type of shoe by industrial organizations reduces accident insurance rates materially.

Referring specifically to the safety shoe itself, it may be stated that as far as general appearance and utility are concerned, this shoe not only approximates the ordinary shoe, but goes further and provides additional protection in that the box portion thereof is strengthened to a high degree.

This type of shoe having a safety feature was sold prior to the development herein shown by the inventor, who is connected with the oldest and possibly best known concern devoting its entire efforts to the production of safety shoes having box members of considerable strength. These box stiffeners were made of an impregnated felt material which provided a fairly satisfactory enclosure and protector for the toes of the wearers of the shoes. As a matter of fact, the present inventor has used, for many years, such felt material in his safety shoes. Desiring, however, to improve his safety shoes and to afford greater protection as well as other advantages to the wearer, he commenced the development of safety shoes which resulted in the present method of shoe construction. This method includes the use of a bakelite or phenolic condensation product box. Bakelite, of course, is a well known substance, but the present applicant, it is believed, found in this substance the real answer to the neces-

sary requirements of his particular business. During his development work he used a great many different kinds of boxes, but in his discovery of bakelite for this particular kind of shoe, such unexpected results were obtained as to cause him to cease further efforts in his search for a material having the highest efficiency for such service.

It is true that this material is more expensive, but the inherent advantages and the unexpected advantages that result from its use, as well as the simplified method of shoe construction that is permitted by its use, overcomes entirely such additional cost.

Referring now specifically to the drawings, there is shown merely the toe portion of a shoe, inasmuch as shoe construction is so well known as to obviate the necessity of showing the remaining portion.

In the drawings, there is shown a bakelite or phenolic condensation box member 10, which is formed in a manner to conform absolutely to the shape of the wearer's foot. It is apparent that for various sizes of shoes, different shapes and sizes of bakelite boxes would obviously be used. This bakelite box stiffener is adapted to be placed in the toe portion of the shoe in a manner to surround the toes of the wearer, this being probably best shown in Fig. 1 of the drawings.

The box stiffener itself is of considerable depth, as may be seen, but not of such width as to deface or distort in any manner the shoe itself, its outer appearance being substantially that of any other shoe.

It may be stated that as far as strength is concerned, this bakelite box is at least three or four times stronger than any type of box used in previously known safety shoes. It is apparent also that by increasing the depth of the bakelite, the strength of the box will be increased in direct proportion to the depth, and therefore the safety factor of the shoe as respects strength may be increased as desired.

The box member is grooved in a V-shaped manner as at 11, to receive the beveled edge 12 of the insole 13. This V-shaped groove is of sufficient size to automatically compensate for any irregularities in size or thickness of the insole. The bakelite box is also beveled at the point 14, or rather at the point where the toes of the wearer are initially forced into the box in such manner as to permit ready entrance of the foot within the shoe, as well as smoothing that portion of the box to prevent pressure at that point upon the wearer's foot.

This bakelite box stiffener is again beveled at the point 15, or rather at its lower and outer edge in such manner as to permit and assist in the passage of the sewing needles thereabout in the later to be described sewing operation.

As may be clearly seen in the drawings, a lining 16 surrounds the bakelite box stiffener and the leather portion 17 of the shoe overlies

the lining, following the contour of said box. A welt 18 of ordinary construction is united by the stitching 19, not only to the insole, but also the lining 16 and leather portion 17. A filler member of any desired material is provided at 20, and the welt 18 is stitched, as at 21, in the usual manner to the outsole 22.

The various elements making up this safety shoe have been described, and it might be well now to describe the method of constructing the shoe.

The bakelite box stiffener is placed upon the last and the insole disposed in the grooved portion provided therefor, the insole, of course, being first skived in the ordinary manner to form the inner welt 23. The lining 16 and leather 17 are then placed about the bakelite toe and pulled over and under the last by a pulling machine, all of the parts, including the welt 18, being stitched to the insole 13 by the single stitching 19. A filler is then provided beneath the insole and the outsole is attached by stitching 21 to the welt 18.

By using this bakelite box member, the method of forming the shoe is simplified to a considerable degree, inasmuch as the ordinary doubler used in previous safety shoe construction, is obviated, and due to the beveling of the outer and bottom edges of the bakelite box, the curved needles of the stitching machine may efficiently follow the lower edge of the bakelite box member and thereby prevent irregularities in such portion.

The smooth surface of the bakelite box stiffener permits the lining and leather to be drawn smoothly thereover, insuring an attractive appearance of the shoe throughout its life.

The manner of placement of the insole within the V-shaped groove prevents the edge of the insole from curling up within the box, due to moisture of any kind, this being common not only in safety shoes but also in other shoes and not only causing discomfort to the wearer but decreasing the life of the shoe.

Having described the construction and method of forming this novel safety shoe, it might be well to set forth some of the advantages that are obtained by the use of this phenolic condensation product box.

In the first place, the shoe is rendered unusually strong by the use of this product. Where the former safety shoe could stand a compression strength test over the center of the toe of the shoe varying from 225 to 300 pounds, the present shoe will stand a compression test of from eight hundred to fourteen hundred pounds. This increased strength is accomplished by a material which is really very light in weight.

This bakelite box has non-absorption qualities which greatly increase its efficiency over the previously known impregnated felt structure which was susceptible not only to the moisture within the shoe, but also to mois-

ture applied to the exterior thereof. Heat obviously affected the impregnated felt box, while bakelite is not susceptible to any degree of heat to which, under ordinary circumstances, a shoe might be subjected. Furthermore, the bakelite box is not susceptible to bodily perspiration nor to most acids and further will give uniform results.

This character of box will retain its strength throughout the life of the shoe and has the further and perhaps greatest quality of all, in that it is elastic to a point where it will shatter and disintegrate at breaking, rather than dent into the wearer's foot, such indentation in practically every instance in safety shoes where metallic boxes are used necessitating the amputation of the toes.

The bakelite box provides an exterior surface which presents at all times an attractive appearance not found in other similar types of shoes. The fact that the exterior surface of the bakelite box is glass-like as well as rounded also serves to obviate accidents in that a heavy article has a tendency to glance off of such a smooth and rounded surface rather than strike directly thereagainst. Further, the glasslike inside finish gives additional comfort to the wearer and may, because of such finish, permit the wearer's foot to be placed immediately adjacent the box, a feature not found in this character of shoe heretofore.

Moreover, we find that the bakelite box is of such composition as will absolutely prevent discoloration of the wearer's hose, this, of course, not being true in shoes where other characters of safety box are used. Obviously, the bakelite box allows the shoe to retain its attractive appearance and dependable strength throughout its life.

As respects the method of forming the shoe, it has been explained before that the ordinary doubler need not be used. The rolled and beveled edge around the top insures protection against friction between the foot and that edge of the box.

As explained before, it is practically impossible for the insole edges to curl up within the toe and cause discomfort to the wearer. The rounding of the lower edges of the box insures an efficient sewing operation. The use of this bakelite box permits uniformity of strength and appearance in different sizes of shoes.

As respects the safety factors which are, of course, more important than all others and which have been set forth throughout this specification, the inventor wishes to reiterate these features not found in any heretofore known safety shoes. In the first place, this box portion has substantially four times the strength of the box used in any other safety shoe. Second, it will retain this strength when coming into contact with moisture, heat and practically all acids. The particular

feature of elasticity up to the breaking point, where the material shatters and disintegrates rather than dents, contributes more than any single feature to the advantages of this particular product in its application to safety 70 shoes.

This product is a non-conductor, therefore having additional advantages in use in industrial work. The method of constructing the shoe, wherein the box is placed around the insole and rests solidly upon the outsole rather than united thereto in the old manner by stitching only, contributes to the strength of the shoe and particularly to the safety 75 features thereof.

There are other phenolic condensation products and synthetic resins in addition to the substance known commercially as "bakelite" having properties similar to the latter, and the term "phenolic condensation 80 product" can be considered for the purposes of this invention also as designating said equivalent substances having the same general chemical structure and properties which would adapt them for use in the manufacture 85 of a safety box toe.

What I claim is:

1. A stiffening element for box toes shaped to conform to the toe portion of a shoe and formed throughout of a phenolic condensation product, and being of such thickness as to provide such strength and rigidity as to resist deformation when subjected to external 95 blows of great force as would ordinarily cause injury to the wearer's foot.

2. A stiffening element for box toes shaped to conform to the toe portion of a shoe and formed throughout of a phenolic condensation product, and being of such thickness as to provide such strength and rigidity as to resist deformation when subjected to external 100 blows of great force as would ordinarily cause injury to the wearer's foot, and said stiffener being provided on its lower edge with a notched portion adapted to receive an abutting edge portion of the sole portion of a shoe when the stiffener is incorporated therein.

In testimony whereof, I have hereunto affixed my signature.

JAMES D. SHEPHERD.
